NONSIFT CARTON

Duryea Bensel, New York, N. Y., assignor, by
mesne assignments, to Albert Borden, New
York, N. Y.

Application December 24, 1935, Serial No. 56,002

3 Claims. (Cl. 229—43)

The present invention relates to cartons, and has for its principal object the provision of means within a carton for maintaining the flap closed ends thereof in a sift proof, sealed condition, at 5 their contacting points.

The carton herein shown is made of paper-board, and as shown, is of standard known construction, and as will be described and shown, in detail, later, is provided with a simple means 10 whereby when the carton is finally closed and glue-sealed, the normally open crevices of the flap closed ends are sealed against the escape of material from within the carton, and at the same time the corners of the top and bottom ends or 15 the closure are rendered rupture proof.

The foregoing, and other features of advantage will be apprehended as the herein description proceeds, and it will be obvious that modifications may be made in the structure herein, without departing from the spirit hereof or the scope of the appended claims.

In the drawing,

Fig. 1 is a layout of the blank of a carton;

Fig. 2 is a fragmentary perspective view of a 25 carton, erected, and in the act of being closed;

Fig. 3 is a view similar to Fig. 2, showing a further stage in closing;

Fig. 4 is a fragmentary perspective view of the carton closed;

Fig. 5 is a section, taken on the line 5—5, Fig. 30 4, looking in the direction of the arrows;

Fig. 6 is a fragmentary, reduced plan view of a 35 blank layout of modified construction; and Fig. 7 is a fragmentary view of a carton corner of Fig. 6 when closed.

The present carton, as disclosed in the blank layout in Fig. 1, comprises four body forming panels 3, 4, 5 and 6 and a glue lap 7, these all being defined from one another by score lines e, f, g and 40 h.

The closing flaps 8, 9, 10, 11 and 8', 9', 10' and 11' are developed from the ends of the body panels, by associate common score lines 1 and 2. The flaps, while hingedly scored from the body blanks 45 are cut from each other by slits such as a, b, c, and d, said slits being terminated at the common score lines 1 and 2.

After the completion of the blank two crevice and corner sealing paper strips A and B, Fig. 1 50 are then glued to the blank by glue strips C—D. These glue strips are preferably placed on the carton blank and are kept below and above the common score lines 1 and 2, respectively, as viewed in Fig. 1, such glue strips being shown by the shaded zones C—D. The glue strips C and D,

at panels 4 and 6, are extended beyond the score lines 1 and 2 to form glue spots 15—15' and 16—16' on the spaced wider flaps 9—11 and 9'—11' respectively, so that when the sifting strip is applied over the score lines 1 and 2, about midway of its width, the portion along the surfaces inside of the edges 18 and 20, Fig. 1, will be spotted to retain that marginal portion of the sifting strip, as at 16, Figs. 2 and 3 from falling inward during the closing operation. The free marginal portions of the sifting strips between the glue spots 15—16 and 15'—16' are also held from disarrangement, when in the flat, for shipping.

As the sealing strips A—B are run down upon and pressed onto said glue strips in such a manner that a portion, of each strip, unglued, lies over the flaps, and therefore, this portion of the strips is free and unattached, except at the glue spots, as just described.

As viewed in Fig. 1, the upper strip C is glued 20 to the body panels by its lower half 21 and the lower strip D is glued to the carton by its upper half 22.

Then the carton is folded flat on its score line g, the glue lap 7 is folded on its score line e and 25 is then glued and is affixed on the inner surface of the body panel 6, adjacent the edge i.

In overfolding and attaching the glue lap 7 to the inner surface of the panel 6 at i, the glue lap carries with it, the extended ends 13—14 of the 30 sifter strips A and B, which are partially glued to the inner face of the glue lap 7 by the extension of the glue strips 1 and 2 upon the glue lap. Thus when the glue lap is affixed, the extensions 13 and 14 of the sifting strip are also infolded over and 35 around the corners formed at the glue lap at the flap junctures, and by overlapping the sifter strip at the corner faces 19 and 20, Figure 1, and as at 25, Fig. 2, the cut corners between flaps 8 and 11, and flaps 8' and 11' are reinforced by the overlapping 40 of the ends of the sifter strip.

The carton is shipped in this flat folded and glued condition to the user, who erects the carton for filling and sealing.

In the further showing, in Figs. 2 to 5 inclusive, 45 only the upper half of the carton is shown, it being understood, from the showing of the blank of Fig. 1, that both closable ends of the carton may be alike.

In Fig. 2, the carton shown erected into rectangular containing position, and having been first closed at its bottom end, and filled, and in the act of being closed.

As the sealing strips C and D, Fig. 1 are free of the flaps on their sealing portions 18 and 17 55

respectively, and are by reason of the glue flap ends 13 and 14 thereof being overlapped to the opposite strip ends 19 and 20, as at 25, Fig. 2, the two strips are made continuous, and form a flexible, inner, foldable liner around the open interior flap surfaces, the sealing strip being thus continuous at the corners and therebetween.

When closing flap 10 is first over-folded as in Fig. 2, it carries down the adjacent continuous portion of the sealing flap, bending down a portion of the sealing flap adjacent closing flaps 8 and 11, angularly, as at 26-27, Fig. 2.

Similarly when opposite flap 8 is bent to closing position, as in Fig. 3, it carries down a portion of the sealing flap adjacent to said closure flap 8, bending a portion of said sealing strip adjacent the closing flaps 9 and 11, angularly, as at 28 and 29, Fig. 3, leaving the sealing flap portions which are adjacent flaps 8 and 11 where spot glued, unclosed, with their connecting corners folded at angles at the four corners of the two closed flaps.

Then while in this position, the two closed flaps 8 and 10 are glued all over on their exposed faces, then flap 9 is folded down upon flaps 8 and 10 and finally, the flap 11 is folded down upon flap 9, and thus the end closing operation is completed, with the portions of the sifting strip on the flaps 9-11 and 9'-11' held between two glued faces, the spots 15-16 and 15'-16' and the glue upon the flaps 8 and 10.

During the closing down of the flaps 8 and 10, the sifting strip, which is unscored, but is of relatively thin paper, tends to buckle at the free marginal portions of the strip adjacent the flaps 9 and 11, and, for this reason the glue spots 15-16 and 15'-16' are utilized to uphold these portions and thereby prevent this buckle and to permit of the angled corners 26, 27, 28 and 29 being readily folded by the closure of the flaps 8 and 10. This arrangement ensures positive action in automatic machine operations of closing this type of carton.

Fig. 5 illustrates, in amplified dimensions, the sealed carton at the sectional line of 5-5, Fig. 4, the various superimposed elements of this sift proof closure, and while the spacings therein indicated are exaggerated for the purpose of easy reading, in actual practice the materials of the carton and sift proof seal being flexible, the superimposed coating closure members are tightly engaged with one another.

From the foregoing it will be seen that all edges and corners protected by the sift proofing strip are held sift tight through the single and multiple overlapping of the sift proof strip, at all points of the folded overlapped flaps thereof.

In Fig. 6, there is shown a portion of a carton blank, similar to Fig. 1, illustrating a further feature of corner reinforcement, of the carton, in which the indices of the various parts are identical with the showing in Fig. 1. In Fig. 6, the slits b-c, by way of example, are shown as terminating a distance j from the score lines 1 and 2. The object of this is shown in Fig. 7, wherein, due to the unscored portions $j-j$, which are provided between all of the flaps 8, 9, 10 and 11, and 8', 9', 10' and 11', of Fig. 1, the bending down of the flaps on their common score lines 1 and 2, to close the carton causes the uncut corner sections j to act as compressed webs j , Fig. 7, thus acting to stiffen said corners and to render these corners sift-proof.

Thus all of the corners on the carton are doubly reinforced, first by the compressed corner webs j , and the diagonal folds 26, 27, 28 and 29 of the sift strip, as well as being doubly sift proofed.

Having thus described my invention what is claimed is:

1. A carton comprising sheet material cut, scored and folded to form a carton including walls; inner and outer flaps joining the ends of said walls; adjacent flaps, when the sheet is flat, contacting and being separated by slits aligned with the corner scores of the walls; a sift-proof lining adhered continuously along the end margins of the walls and extending against the flaps, and secured to the outer flaps at a central portion of the flap; said lining at said inner flaps and the end areas of the outer flaps being unsecured; said portion being near enough to the ends of the outer flaps, to hold said lining firmly against the faces of the inner flaps when the inner flaps are closed; said slits extending near enough to the walls to avoid interference with flap closing or flap tearing during closing; the slits being remote enough from the walls to form an effective shock-absorbing, lining-protecting continuous reinforcing corner web when the flaps are all closed; side and hinged edges of the inner flaps and all edges of the outer flaps extending substantially to said walls and the entire top face of the inner flaps being covered with adhesive and one outer flap pressed thereon, whereby the lining is adhered between two faces and rendered sift-proof.

2. A carton comprising a sheet of material cut, scored and folded to form a carton including body walls; inner and outer flaps foldably joining the ends of said walls; adjacent flaps, when the sheet is flat, contacting and being separated by a slit aligned with the corners of the carton; a sift-proof lining adhered continuously along the end margins of the walls and extending a distance against the flaps, and secured to the central portion of the outer flaps; said lining at said inner flaps and the end areas of the outer flaps being unsecured; said portion of the outer flaps extending near enough to the ends of the outer flaps, to hold said lining firmly against the inner flaps when the inner flaps are closed and each outer flap is open in the plane of its wall, whereby adhesive at the inner flap is unnecessary; said slits being near enough to the walls to avoid interference with flap closing or flap tearing during closing; the slits being remote enough from the walls to form an effective uncut-, full-thickness, compressed, shock-absorbing lining-protecting, continuous, sift-proof, reinforcing corner web when the flaps are closed; the outer flaps extending at all sides substantially to said walls, and the entire top face of the inner flap being covered with adhesive and an outer flap pressed thereon, whereby the lining is adhered between two faces and rendered completely sift-proof.

3. A carton comprising a flat sheet of material cut, scored and folded to form a carton including body walls; inner and outer flaps foldably joining the ends of said walls, adjacent flaps, when the sheet is flat, contacting and separated by slits aligned with the corner scores of the walls; a pliable sift-proof lining adhered continuously along the end margins of the walls adjacent to the flaps and extending against the face of the flaps a distance from the walls, and secured to the outer flaps at an area extending from the inner margin of the flaps to the outer edge of the lining; said lining at the end areas of the outer flaps being unsecured; the secured area at the outer flaps extending near enough to the ends of the outer flaps, to hold said lining firmly against the inner flaps when the inner flaps are closed and each outer flap is open in the plane of its wall; said

slits extending near enough to the walls to avoid interference with flap closing or flap tearing during closing; the slits being remote enough from the walls to form an effective shock-absorbing continuous reinforcing corner web when the flaps are all closed, thereby to protect the lining at

the corners; the outer flaps extending on all sides substantially to said body walls; all parts of said webs and flaps being the full thickness of the sheet.
